UNITED STATES PATENT OFFICE.

MICHAEL ANDREW DROITCOUR, OF OAK PARK, ILLINOIS, ASSIGNOR TO MIEHLE PRINTING PRESS AND MANUFACTURING COMPANY, OF CHICAGO, ILLINOIS, A CORPORATION OF ILLINOIS.

SHEET-DELIVERY MECHANISM FOR ROTARY PRINTING-PRESSES.

1,078,097.

Specification of Letters Patent.

Patented Nov. 18, 1913.

Application filed March 2, 1911. Serial No. 611,839.

To all whom it may concern:

Be it known that I, MICHAEL A. DROITCOUR, of Oak Park, in the county of Cook and State of Illinois, have invented certain new and useful Improvements in Sheet-Delivery Mechanism for Rotary Printing-Presses; and I hereby declare that the following is a full, clear, and exact description thereof, reference being had to the accompanying drawings, which form part of this specification.

This invention is an improvement in sheet delivery mechanism, especially adapted for use in connection with rotary sheet printing presses of the type shown in my Patent No. 983,219 of January 31, 1911.

The primary object of the invention is to enable the successive printed sheets to be delivered alternately at opposite ends of the press, by means of a novel delivery mechanism comprising sets of extensible and contractible tapes adapted to carry sheets first to one table, and then to the other. Novel means are provided for stopping the linear travel or running of one set of tapes, and simultaneously driving the other set of tapes. Also novel means are provided for starting and stopping the tapes gradually, and by which the tapes can be caused to move the sheets outward over the tables at a speed equal to that of the printing cylinders; and faster than the travel of the delivery carriage, so as to cause the sheets to be brought up to the ends of the carriage and properly positioned over the delivery tables, before the tapes are retracted and the sheets dropped.

The invention also includes novel means for looping the tapes; novel means for propelling the tapes alternately in opposite directions; novel means for stopping the linear travel of the tapes during the dropping of a sheet; and novel means for reciprocating the tape delivery carriage.

I will describe the invention with reference to the accompanying drawings, and summarize in the claims the novel features and combinations of parts for which protection is desired.

In said drawings—Figure 1 is a conventional diagrammatical sectional elevation of part of a printing press showing my novel sheet delivery mechanism applied thereto. Fig. 2 is an enlarged view of the delivery

mechanism, showing the parts in different 55 position from that in Fig. 1. Fig. 3 is a top plan view of Fig. 1 with the printing cylinders and reels removed, and partly in section. Fig. 4 is a detail sectional view of part of the mechanism for operating the 60 tape carriage. Fig. 5 is an enlarged detail sectional view illustrating the gearing for actuating the carriage and tape rollers.

The delivery mechanism is only conventionally shown in the drawings, but in connection with the following description, will enable any one skilled in the art to construct a delivery and apply the same to any suitable make of rotary sheet printing press with which it may be desired to use it.

In the drawings, P represents the plate or printing cylinder of the press; I the impression cylinder; T a transfer reel which is adapted to take sheets from the impression cylinder I and deliver the sheets alternately 75 to the right hand delivery tapes; and to a second transfer reel t which delivers the sheets it receives from reel T, to the left hand delivery tapes. At opposite sides of the reels T, t, are located the delivery tables 80 D and d, which may be of any suitable construction.

Mounted to reciprocate in a horizontal plane below the printing mechanism and reels T, t, and above tables D and d is a 85 delivery carriage which may be composed of opposite bars 1 suitably mounted to reciprocate below the reels, and each bar 1 may be provided on its under side with a rack 1^a, adapted to mesh with a pinion 2^a 90 on shafts 2 journaled in the side frames F of the press, and in brackets f attached thereto, and which shafts have pinions 2^b on their outer ends meshing with gears 2^c on a through-shaft 2^d which is provided 95 with a gear 2^e that meshes with a rack 3^a on the under side of a reciprocating bar 3, which is mounted in suitable brackets or guides attached to the frame of the press. Bar 3 is provided with a scotch-yoke, or 100 slotted head, 3^b, that is engaged by a pin 3^c attached to a chain 3^d which is mounted upon sprockets 3^e and 3^f attached to stub shafts journaled in the frame; and on the shaft 3^g of pulley 3^e is a gear 3^h which 105 meshes with an intermediate gear 3ⁱ that meshes with a gear t' on the shaft of the reel t. The gear 3^h may be driven in any suitable

way and should be driven at such speed as will cause the bar 3 to make one complete reciprocation for each two revolutions of the plate cylinder P, or for every two sheets printed by the machine. By means of this driving arrangement the carriage 1 will be reciprocated at the desired time and will for the major portion of its stroke be traveled at uniform speed, while the wrist pin 3^c is moving between the sprockets 3^e and 3^f, but will be slowed down, stopped and reversed with a true crank motion at each end of its stroke, while the wrist pin 3^c is passing around sprocket 3^e or 3^f.

At opposite sides of the shaft 2^d are mounted vertically movable bars 4 and 5; the bars 4 have rack portions 4^a which mesh with gears 2^e on the shaft 2^d, and the bars 5 have rack portions 5^a which also mesh with opposite sides of the gears 2^e so that as the gear 2^e oscillates one set of rack bars is raised while the other set is depressed.

The rack bars 4 carry rollers 4^b, 4^c at their lower ends and the rack bars 5 carry rollers 5^b, 5^c. The bars are guided in suitable brackets attached to the frame. Journaled in these brackets at one side of and above the shaft 2^d is a set of tape rollers 4^d, 4^e, 4^f, 4^g; and journaled in the brackets at the opposite side of and above shaft 2^d, is a set of tape rollers 5^d, 5^e, 5^f, 5^g. Journaled in opposite ends of the carriage 1 are tape rollers 4^h, 5^h respectively. A set of endless tapes 4^t run over roller 4^h, to and over roller 4^d, down under roller 4^b, up over roller 4^e, down under roller 4^c, up over roller 4^f, down and around roller 4^g, and back to roller 4^h. A similar set of tapes 5^t run over roller 5^h, to and over roller 5^d, down under roller 5^c, up over roller 5^g, down under roller 5^b, up over roller 5^f, to and around roller 5^e, and thence back to roller 5^h. As the carriage 1 reciprocates the rollers 4^h, 5^h are alternately moved to and from the rollers 4^d, 5^d; and the rack bars 4 and 5 are alternately raised and lowered so as to take up or give out tape, in or from the loops on the rollers on said rack bars, as may be required by the movement of the rollers 4^h, 5^h. For example, as roller 4^h moves inward the rollers 4^b, 4^c are lowered so as to take up the loop of tape paid in from the roller 4^h; and simultaneously the roller 5^h moves outward and the rollers 5^b, 5^c rise and pay out from their loops enough tape to supply the elongation of the loop around roller 5^h (see Fig. 1).

Intermediate the rollers 5^d, 4^h is a tape propelling roll 6 which is journaled in arms 6^a pivoted at 6^b on brackets attached to the frame. This propelling roll is adapted to be alternately brought into contact with the tape rollers 4^d or 5^d so as to propel the sets of tapes running thereover. The roller 6

may be driven and rotated in the proper direction and time by means of a pinion 6^c thereon meshing with a rack 1^e on the adjacent side bar of the carriage 1. The propelling roller 6 may be moved into contact with the tape rollers 4^d or 5^d at the proper time, and be held in contact therewith, by means of a pitman 6^d having a roller 6^e engaging a race-cam 6^f attached to a stub-shaft 6^g carrying a gear 6^g which may be driven by a pinion 6^h attached to a shaft 6ⁱ, on which is a gear 6^j that meshes with a gear 6^k which may be fixed on the main drive shaft 6^m of the machine. The reel T may have a gear T' also meshing with the gear 6^j.

Attached to the arms 6^a, are depending arms 6^l which carry clamp members 6° which operate between the adjacent vertical runs of the tapes 4^t, 5^t, and between stop bars 4°, 5° adjacent tapes 4^t, and 5^t, see Figs. 1 and 2. These stop bars 4°, 5° are so located that when the propelling roller 6 is moved into contact with the roller 5^d it will drive tapes 5^t and clamp 6° nips tapes 4^t against stop bar 4° and stops the linear travel of tapes 4^t over their rollers, except such as may be required to compensate for the extension and contraction of their loops. Similarly, when propelling roller 6 is moved into contact with tape roller 4^d in order to drive tapes 4^t, the tapes 5^t are nipped by the clamp 6° against stop bar 5° and held against linear travel; except such as may be required by the extension and contraction of the loops in said tapes. The tapes 4^t are held only when the roller 4^h is moving inward and the tapes 5^t are so held only when the roller 5^h is moving inward. When roller 4^h for example is moving inward and the roller 6 drives tapes 5^t, and the tapes 4^t are held from traveling over the rolls 4^d, 4^h.

Above the path of the carriage and above table D is a set of rider tapes 7 running over fixed rollers 7^a, 7^b; and said rollers may be driven correspondingly with the tapes 4^t at the proper time by means of a cross belt 7^c driving roller 7^a from roller 4^d. Above the table d is a similar set of rider tapes 8 running over rollers 8^a, 8^b and driven by a cross belt 8^c from the tape roller 5^d.

When the parts are in the position shown in Fig. 1 it may be assumed that a sheet has been taken from reel t and carried out by tapes 5^t over the table d. Another sheet is then ready to be delivered by reel T to the tapes 4^t. The carriage will then move to the right, and as the carriage starts roll 6 is moved over against roll 4^d, (see Fig. 2), and the clamp 6° nips tapes 5^t against stop 5°. As the carriage moves to the right tapes 4^t are traveled at the speed of the cylinder, and the sheet received from reel T is carried out on tapes 4^t, toward roller 4^h, to and over table D, the sheet coming into proper posi-

tion over table D as the carriage reaches the end of its right hand stroke, where it is slowed down and stopped during the passage of the pin 3^c around the sprocket 3^f .

5 During this time the sheet has been dropped from tapes 5^e onto the table d . The parts then reach the position shown in Fig. 2, and at this time a sheet has been transferred to the reel t and is ready to be delivered onto the tapes 5^e . Then the carriage moves to the left and a sheet is delivered from reel t to tapes 5^e and carried out to and over table d , until the parts assume the position shown in Fig. 1; meanwhile the sheet which had been carried out on tapes 4^e is dropped upon the table D, by the tapes 4^e and roller 4^h withdrawing from beneath the sheet. When the carriage starts to the left roll 6 is moved over against roller 5^h so as to propel tapes 5^e and simultaneously clamp 6^a nips tapes 4^e against clamp 4^g ; and consequently as the carriage moves to the left the roller 4^h and the tapes 4^e simply withdraw from beneath the sheet and allow it to drop upon the table D. Upon the next right hand stroke of the carriage another sheet will be taken from reel T out upon tapes 4^e ; and simultaneously roller 5^h and tapes 5^e will be withdrawn from beneath the sheet over table d and permit the sheet to drop thereupon. In this way it will be observed that the sheets are alternately taken to tables D, d , all the sheets transferred to reel t being delivered to table d ; and the alternate sheets being delivered by reel T to tapes 4^e . When one set of tapes is being projected outward to carry a sheet from the reel to the table, such tapes are driven so that they move at the surface speed of the reels or cylinder; such tapes are preferably traveled at a speed slightly greater than the linear movement of the carriage, by having the roll 6 slightly larger in diameter than gear 6^e . The tapes are preferably moved a little faster than the carriage so that the forward edge of the sheet can catch up with the roller 5^h (or 4^h) on its outward movement, and be in position to be properly dropped upon the table during the inward movement of such roller. The tapes and sheet are caused to stop gradually as the carriage reaches the end of its stroke, while the wrist pin is passing around sprocket 3^g , or 3^f , so that the sheet is not apt to be displaced by momentum. The roller 6 and the clamp 6^a are shifted to engage the opposite sets of tapes at the moment that the latter have practically ceased to travel and during the reversal of the carriage. By this means successive sheets printed by one mechanism of any suitable kind, may be alternately delivered to different feed tables; and thus ample time is allowed for each sheet to settle properly into place upon its table before another sheet is dropped thereupon; and

the printing mechanism can be operated at high speed, while the delivery of the sheets can take place at practically half the speed at which they are printed.

What I claim is:

1. In sheet delivery mechanism, a pair of delivery tables, a set of extensible and contractible tapes for delivering sheets to each table; a single carriage, and means thereon for extending one set of tapes over one table and simultaneously withdrawing the other set from above the other table; means for looping these tapes to compensate for the extension and contraction thereof; and means for driving either set of tapes while it is carrying a sheet outward, and for stopping the linear travel of the other set of tapes while it is being contracted. 70

2. In combination, a reciprocating carriage, a pair of delivery tables, rollers on said carriage adapted to be projected alternately over the said tables; stationary rollers intermediate the rollers on the carriage, oppositely movable sets of looping rollers adjacent the stationary rollers; and sets of endless tapes respectively running over one set of looping rollers one set of stationary rollers and the related roller on the carriage; so that one set of tapes is retracted from over one table while the other set of tapes is projected over the other table, and vice versa; and means for driving the set of tapes being projected and simultaneously stopping the set of tapes being retracted. 85

3. In combination, a reciprocating carriage, sheet receiving tables at opposite sides of said carriage; rollers on the ends of said carriage adapted to be alternately moved over the related table; a set of stationary tape guiding rollers intermediate the rollers on the carriage; a set of vertically movable looping rollers adjacent the stationary rollers; sets of tapes running over the related looping rollers, stationary rollers and carriage rollers, one set of tapes being retracted as the other set is projected; with a shifting driven roller; and means for causing the driven roller to propel the sets of tapes alternately. 100

4. Sheet delivery mechanism comprising opposite sheet receiving tables; a reciprocating carriage, tape rollers at the opposite ends of the carriage, sets of stationary located tape rollers intermediate the rollers on the carriage; a set of movable looping rollers adjacent each set of stationary tape rollers; a set of tapes running over one of the rollers on the end of the carriage and the related set of stationary tape rollers and related set of looping rollers; means for reciprocating the carriage; means for simultaneously shifting the sets of looping rollers so that when one set of tapes is projected over the related table the opposite set of tapes is retracted; a driving roller 115

located intermediate the sets of tapes; and means for causing the driving roller to alternately engage the sets of tapes so as to propel the tapes that are being projected over a table, and means for arresting the set of tapes that are being retracted.

5. In delivery mechanism, the combination of a reciprocating carriage, a reciprocating rack bar, gearing between the rack bar and carriage, adjacent sets of stationarily fixed tape rollers; a set of tape looping rollers adjacent each set of stationary tape rollers; means for reciprocating the sets of looping rollers in opposite directions; tape rollers on the opposite ends of the carriage; a set of tapes running over a tape roller on the carriage, and the related sets of stationary and looping rollers; whereby when the carriage is reciprocated the sets of tapes are alternately projected and contracted over the adjacent feed tables, substantially as described.

6. In delivery mechanism, the combination of a reciprocating carriage, a reciprocating rack bar, gearing between the rack bar and carriage, an endless chain, a wrist pin on the chain for actuating the rack bar, adjacent sets of stationarily fixed tape rollers; a set of tape looping rollers adjacent each set of stationary tape rollers; means for reciprocating the sets of looping rollers in opposite directions; tape rollers on the opposite ends of the carriage; a set of tapes running over a tape roller on the carriage, and the related sets of stationary and looping rollers; whereby when the carriage is reciprocated the sets of tapes are alternately projected and contracted over the adjacent feed tables; and means for stopping the tapes while being retracted and traveling the tapes while being projected.

7. In sheet delivery mechanism for printing presses, the combination of a printing mechanism, a pair of sheet receiving tables, a set of extensible and contractible tapes for each feed table; a single carriage and devices thereon for extending one set of tapes over one table and simultaneously withdrawing the other set from above the other table; means for looping the sets of tapes to compensate for their extension and contraction; and means for driving the set of tapes carrying a sheet outward, and for stopping the travel of the other set of tapes which is being contracted.

8. In combination, a printing mechanism, a reciprocating carriage below said mechanism, a pair of sheet receiving tables below the carriage; tape rollers on said carriage adapted to be projected alternately over the said tables; stationary tape rollers intermediate the rollers on the carriage; oppositely movable sets of tape looping rollers adjacent the stationary rollers; opposite sets of endless tapes each running over a

looping roller on the carriage and the related stationary rollers and looping rollers so that one set of tapes is contracted when the other set of tapes is projected, and vice versa; and means for simultaneously driving the set of tapes being projected and simultaneously stopping the set of tapes being retracted.

9. In combination, a printing mechanism, a pair of delivery reels, a reciprocating carriage below the delivery reels, sheet receiving tables adjacent opposite ends of said carriage; tape rollers on the ends of said carriage; sets of relatively stationary tape guiding rollers below the reels; sets of vertically movable tape looping rollers adjacent the stationary rollers; sets of tapes running over the respective carriage rollers and related looping and stationary rollers, so that one set of tapes will be retracted as the other set is projected; a driven roller, means for causing the driven roller to propel the sets of tapes alternately, and means for simultaneously stopping the other set of tapes.

10. In sheet delivery mechanism, the combination of printing mechanism, opposite delivery tables; a reciprocating carriage, crank mechanism for reciprocating said carriage; tape rollers at opposite ends of the carriage, sets of stationarily located rollers intermediate the rollers on the carriage; sets of movable looping rollers adjacent each of the sets of stationary tape rollers; sets of tapes respectively running over one of the rollers on the carriage and over the related sets of stationary tape rollers and tape looping rollers; and means for simultaneously shifting the sets of looping rollers so that when one set of tapes is projected over the related table the opposite set of tapes is retracted; with a driving roller located intermediate the sets of tapes; means for causing the driving roller to alternately engage the tapes so as to propel the set of tapes that is being projected over a table, and means for simultaneously arresting the set of tapes that is being retracted.

11. In delivery mechanism, the combination of a reciprocating carriage, a reciprocating rack bar, gearing between the rack bar and carriage for reciprocating the latter from the rack bar, an endless chain; means for driving the chain, and a wrist pin on the chain for actuating the rack bar; with adjacent sets of stationarily fixed tape rollers, a set of looping rollers adjacent each set of stationary tape rollers; means for reciprocating these looping rollers in opposite directions; tape rollers on the opposite ends of the carriage; sets of tapes respectively running over one of the tape rollers on the carriage, and over the related sets of stationary rollers and looping rollers; whereby when the carriage is reciprocated the sets of tapes are alternately projected and

contracted over the adjacent feed tables, substantially as described.

12. In delivery mechanism, the combination of a reciprocating carriage, a reciprocating rack bar, gearing between the rack bar and carriage for reciprocating the latter from the rack bar; means for actuating the rack bar, adjacent sets of stationary tape rollers; a set of looping rollers adjacent to each set of stationary tape rollers; means for reciprocating the sets of looping rollers in opposite directions; tape rollers on opposite ends of the carriage; sets of tapes respectively running over a tape roller on the carriage, and over the related sets of stationary and looping rollers, whereby when the carriage is reciprocated the sets of tapes are alternately projected and contracted over the adjacent feed tables; with a movable tape driving roller; means for shifting said roller alternately into engagement with the opposite sets of tapes so as to drive the set of tapes that is being projected over a table; and a shiftable clamp

adapted to alternately engage the sets of tapes whereby when one set of tapes is being driven by the roller the other set of tapes is stopped by the clamp.

13. In combination, a rotary printing mechanism, adjacent sheet receiving tables 30 below and at opposite sides of the printing mechanism, a carriage, and means for reciprocating the carriage below the printing mechanism and above and between the tables; with sets of extensible and contractible tapes at opposite sides of and operated by the carriage said tapes receiving sheets alternately from the printing mechanism and delivering the sheets alternately from opposite ends of the carriage to the respective tables.

In testimony that I claim the foregoing as my own, I affix my signature in presence of two witnesses.

MICHAEL ANDREW DROITCOUR.
